UNITED STATES PATENT OFFICE

132,627

DESIGN FOR A RADIATOR FOR A SEWING MACHINE

Malcolm S. Park, Mount Kisco, N. Y., assignor
to The Singer Manufacturing Company, Eliza-
beth, N. J., a corporation of New Jersey

Application April 18, 1942, Serial No. 106,617

Term of patent 14 years

To all whom it may concern:

Be it known that I, Malcolm S. Park, a citizen
of the United States, residing at Mount Kisco,
in the county of Westchester and State of New
York, have invented a new, original, and orna-
mental Design for a Radiator for a Sewing Ma-
chine, of which the following is a specification,
reference being had to the accompanying draw-
ing, forming a part thereof.

Fig. 1 is a rear perspective view of a radiator
for sewing machines showing my new design.

Fig. 2 is a perspective view of the radiator for
sewing machines shown in Fig. 1, but looking
in the opposite direction.

I claim:

The ornamental design for a radiator for a
sewing machine, as shown.
